INTERURBAN TELEPHONE SYSTEM

Claudius F. Stewart and Gabriel J. M. Penet,
 Paris, France, assignors to International Standard Electric Corporation, New York, N. Y., a corporation of Delaware

Application September 27, 1943, Serial No. 504,084
 In France June 13, 1939

8 Claims. (Cl. 179—27)

1

The present invention relates to new and useful improvements in telephone systems comprising exchanges connected by inter-urban toll trunk lines in which calls between subscribers of different exchanges may be established by the operator at the outgoing central exchange, without the assistance of the operator at the incoming central exchange, the operator at the outgoing exchange being, nevertheless, able to call and communicate with the operator of the incoming exchange.

More particularly, the invention relates to systems in which the required instructions, or signals, are transmitted in the form of A. C. impulses of a single frequency. Known systems of this type have the serious drawback that, for one reason or another, the normal impulse transmitting cycle between the exchanges gets out of order, and it may happen that the incoming equipments at the two exchanges are interconnected through an inter-urban toll circuit in such a way that their automatic release at the end of the conversation will be impossible.

In accordance with one of the features of the invention, this drawback is eliminated by making the switching and release impulses sent from the outgoing exchange long, while the return impulses sent from the call exchange short. The direction, or effect of the short and long impulses on a circuit, is fixed by the outgoing exchange and cannot be reversed, or changed, even if the transmission cycle is interfered with, unless the outgoing equipment of the said outgoing exchange has been released, that is to say, unless the incoming exchange has become the outgoing exchange after complete release of the first outgoing exchange. Thus, it is made impossible that input equipment in the two exchanges may become interconnected.

Other characteristics features of the invention will more fully appear from the description which will be given with reference to the attached drawings, which diagrammatically represent:

Fig. 1, an outgoing equipment used in conjunction with inter-urban switchboards in which the dialling key may cause switching in the circuit equipment;

Fig. 2, an input equipment in conjunction with the inter-urban boards, and an automatic switchboard;

Fig. 3, a re-transmitter recorder operating in conjunction with the input equipment;

Fig. 4, equipment comprising a group of operator calling relays designed to be introduced between the input equipment and the inter-urban switchboard;

Fig. 5, outgoing equipment used in conjunction

with inter-urban switchboards in which the dialling key does not cause switching in the circuit equipment;

Fig. 6, input equipment for the exchange, not including an automatic switchboard; and

Fig. 7, the manner in which the different Figs. 1 to 6 should be connected.

In the description which follows the relay contacts which are closed when the relay is energized, that is to say, in operating position, are designated by placing the letter T in front of the number of the spring, and the contacts which are closed when the relay is not energized, that is to say, in non-operating position, by placing the letter R in front of the number of the spring. The contacts of the make and break switches are shown on the figures by shaded squares provided with reference numerals designating the positions of the wipers, for which the make and break switch closes the contact and with reference letters identifying the wiper of the make and break switch which closes the contact.

First, with reference to Fig. 1, the detailed operation of the outgoing equipment will be described.

25 This equipment is designed to be used in conjunction with the operator's position in which the operator operates a key or button before and after dialling the number of the called subscriber, the call from the operator at the incoming exchange being established by operating a key or calling button.

It is assumed that the toll operator at exchange A (Fig. 7) wishes to call a subscriber in exchange B.

35 Normally, when the apparatus are disengaged, the relay 3 of the input equipment (Fig. 2) is energized in the circuit: battery, winding of 3, R41, R51, R21 and earth. Relay 3 of the outgoing equipment (Fig. 1) is energized in the circuit: battery, wiper a of the make and break switch in position 0, wire C, T32, R51, R21 and earth. At T32 (Fig. 1) the circuit of the disengaged lamp In is established.

By operating the lighting-up key L (Fig. 1), 45 the operator A can make sure that the equipment is disengaged. She then plugs one of her cord circuits in the calling jack J1. The following circuit for relay 1 (Fig. 1) is completed: battery, winding of the relay 1, R153', T13, body of the jack J1, and earth through the relays of the third or sleeve wire of the cord circuit which are not shown. At T12, the relay 1 establishes the circuit of relay 13' which insulates at R132' and R131' the outgoing equipment of Fig. 1 from the incoming equipment in Fig. 2, and connects the said

outgoing equipment to the inter-urban circuit L_1-L_2 .

Over $T12$, the relay 1 closes through wiper C of the make and break switch in the position 0, the circuit of the stepping magnet Cm_1 of the make and break switch. The magnet Cm_1 attracts its armature, breaks its own circuit, and steps the wipers of the switch by one step into position 1.

The circuit of the relay 8 is closed by the wiper a of the switch in the position 1. At $T81$, the relay 8 establishes the circuit of the upper winding of the relay 9 which, in $T93$, closes the following circuit for the relay 7: battery, non-inductive upper winding of the relay 7, $T93$, lower winding of 7 and earth. The relay 7 closes its holding circuit at $T12$.

The alternating current of the generator G_1 is transmitted over the inter-urban circuit L_1-L_2 through $T92$, $T132$, conductor L_1 and $T91$, $T131$, conductor L_2 to the receiving equipment of the exchange B.

When the make and break switch moves into position 1, the circuit of the relay 3 is opened in the wiper a and this relay drops.

When the operator A depresses her dialling key battery is applied to the ring wire n of the jack J_1 and the following circuit is closed for relay 5: battery on the ring n of J_1 , $R124$, series windings of relay 5, $T11$, wiper e of the switch in position 1 and earth. The relay 5 locks up over $T52$ and through $T51$ closes a circuit for the lower winding of the relay 16, which becomes energized.

The stepping circuit of the switch is closed: earth, interrupter Ca_1 , wiper c in position 1, $T163$, magnet Cm_1 and battery. The switch advances step by step. When the wipers have passed position 4, the circuit of the relay 8 through the wiper a is opened, and this relay drops. At $T81$, the relay 8 opens the circuit of the upper winding of 9, which drops. At $R93$, the relay 9 short-circuits the lower inductive winding of 7, which drops. When the relay 9 has dropped, conductors L_1-L_2 of the trunk line are disconnected from generator G_1 and the transmission of alternating current is terminated. The duration of the transmission from the moment when the operator depresses her dialling key, is determined by the time taken by the make and break switch to advance from position 1 to position 5 under the control of interrupter Ca_1 . A long impulse is thus transmitted to the input equipment (such as that in Fig. 2) of the called distant exchange B.

When the make and break switch reaches position 5, the circuit of magnet Cm_1 is closed through the wiper c in positions 5 to 10 to the cam Ca_1 . In position 11, the circuit of the magnet is closed to the earth at $R151$ and the wiper b of the make and break switch. For the positions 12 to 21, the circuit of the magnet is closed to earth in $R121$ via the wiper f of the switch.

These operations are repeated; that is to say, the relay 8 is energized, the relay 9 is energized, and there is transmitted over the toll trunk circuit L_1-L_2 an A. C. long impulse (for example, 700 milliseconds). The transmission is stopped for a certain period (say one second), new long impulse, etc., until a short impulse (100 milliseconds, for example) is sent by the input equipment of the distant exchange B, and is received by the outgoing equipment, Fig. 1. This impulse is received by the relay 2 through:

conductor L_1 , $T132$, $R92$, $R113$, relay 2, $R111$, $R91$, $T131$, conductor L_2 .

Through $T21$, the relay 2 completes the circuit of the lower winding of the relay 11 which, by means of its springs 111 and 113, cuts off the conductors L_1-L_2 from the relay 2, and connects them to the relay 4. Relay 4 in this way receives the rest of the impulse emanating from the B exchange. The relay 11 whose new circuit is closed at $T41$, is held during this transfer, as it is retarded in release by its upper winding which is short-circuited by $T114$. The following circuit for the relay 15 is then closed: earth, $T41$, $R141$, $R151$, lower winding of the relay 15 and battery.

When the impulse has been received, the relay 4 drops. The relay 15 is held over the lower winding of 15', $T152$, $T12$ and earth. The relay 15' is energized. The following circuit for relay 12 is then established: earth, upper winding of 12, $T154$, non-inductive lower winding of 12 and battery. The relay 12 is held and closes its holding circuit at $T122$.

At $R151$, the stepping circuit of the make and break switch is open in position 11, and the switch stops in this position.

The non-inductive lower winding of the relay 1 is no longer short-circuited in $R153$ which causes the lamp of the cord circuit plugged in at J_1 to light up. The operator is thus advised and perceives the signal transmitted by the distant exchange. She then proceeds to dial the called subscriber's number.

The dial impulses are repeated by the relay 9 whose circuit is closed via the contact of the said dial: earth, lower winding of 9, wiper a of the make and break switch in positions 6 to 10, or wiper d in position 11, $T166$, tip p of the jack J_1 and of the plug of the cord circuit and the dial in the cord circuit to battery.

Each time the relay 9 energizes, it connects the conductors L_1-L_2 to the generator G_1 , and an A. C. dialling impulse is sent to the distant exchange B.

The relay 7 is energized by the first impulse of each train of impulses and holds during the train of impulses, and drops only during the period between trains of impulses. This relay drops only for a moment at the end of a train of impulses, and the line conductors L_1-L_2 are bridged through $T71$ in order to discharge the line and thus insure the stable transmission of the impulses.

When the operator has completed dialling the called number, she releases the dial key which opens the circuit of the relay 5 through ring contact n , and relay 5 opens at $T51$ the circuit of the relay 16. The make and break switch advances by one step, the circuit of its magnet being closed via: earth, $R164$, $T151$, wiper b of the switch in position 11, contact and winding of the magnet, and battery.

The relay 16 is again energized over its upper winding via: battery, upper winding of 16, wiper d of the switch in position 12, $T123$ and earth.

The make and break switch is then advanced from position 12 to position 16, the circuit of its stepping magnet being closed via: earth, cam Ca_1 , wiper b in positions 12 to 15, $T163$, magnet Cm_1 and battery.

The circuit of the relay 8 has been established via: battery, winding 8, $T165$, wiper d of the switch in positions 12 to 15, $T123$, and earth. The relay 8 closes the circuit of relay 9 which transmits an A. C. impulse to L_1-L_2 .

5

When the switch reaches position 16, the circuit of the upper winding of the relay 16 is opened, this relay opens at T163 the stepping circuit of the switch, and at T165 the circuit of relay 8 which drops and causes relay 9 to drop.

While the wipers of the make and break switch are moved from position 12 to position 16 under the control of the cam Ca1, a long A. C. impulse (say 700 milliseconds) is sent to the exchange B.

If the called subscriber is engaged, the operator will notice the busy signal sent by the distant exchange. When the called subscriber lifts his receiver, a short impulse (say 100 milliseconds) is transmitted by the exchange B and is received on the relay 2 (Fig. 1) of exchange A. The relay 2 causes relays 11 and 4 to energize. Relay 4 closes the following circuit for the upper winding of relay 15: earth, T41, R141', T151', T154, upper winding of 15 and battery. As the two windings 15 are fed in opposition, the armature of this relay drops. The relay 15' is energized over its upper winding by T151', R141', T41 and earth.

At the end of the long impulse, the relay 4 drops, and the relay 15', whose upper winding is open, also drops. At R153', the relay 15' short-circuits the lower non-inductive high resistance winding of 1. The cord circuit lamp indicator goes out, thus advising the operator that the called subscriber has answered.

The operator completes the call over the second plug of her cord circuit.

When the conversation is terminated and the called subscriber replaces his receiver, a short A. C. impulse is transmitted from the distant exchange B. It is received by the relay 2 (Fig. 1) of exchange A and causes relays 11 and 4 to operate, as above described. The relay 15 is energized over its upper winding and is maintained in series with 15', as has already been shown. The lower non-inductive high resistance winding of 1 is short-circuited by R153' which causes the cord circuit indicator lamp to light up, thus telling the operator that the call has been terminated.

When the operator removes the plugs, the circuit of the relay 1 is opened and this relay drops. The relay 13' is held by earth at T121. The relay 16 is energized on its lower winding via: battery, lower winding of 16, R12, T121 and earth.

The stepping circuit of the make and break switch is established via: earth, cam Ca2, wiper b of the switch in positions 16-18. The relay 8 is energized in the circuit: battery, relay 8, T165, wiper d of the switch in the positions 17 to 19, T123 and earth. The relay 9 is energized over T81 and the relay 7 over T93.

A long releasing impulse (approximately one second, for example) is transmitted to the exchange B by T91 and T92 during the time that the make and break switch is being moved to position 19. When the make and break switch arrives in position 19, the relay 12 is short-circuited by the wiper b and drops. The relays 16 and 8 drop, their circuit being opened at T123. At T181, the relay 8 opens the circuit of the relay 9 which drops and short-circuits at R93, the relay 7 which also drops. Relays 13', 15 and 15', whose circuit is open at T121, drop.

The make and break switch returns to normal via the following circuit: earth, R121, wiper f in positions 12 to 21, contact and winding of magnet Cm1 and battery. When the switch arrives in position 0, its stepping circuit is open.

The relay 3, whose circuit is again completed 70

6

by the wiper a in position 0, applies battery to the disengaged indicator lamps In.

The mechanism of Fig. 1 is now available for the setting up of a new call.

5 We shall now describe how the operator at exchange A, for example, may call the operator of exchange B.

When the operator at the exchange A plugs in, the same operations as those just described occur until the first A. C. impulse is transmitted from exchange A to exchange B. The operator at exchange A then operates her calling key. The circuit of relay 2 is closed through the cord circuit via: tip p, R132, relay 2, R131 and ring n of J1. The relay 2 closes at T21 the circuit of the lower winding of relay 11 which is energized. At T112, the relay 11 closes the following circuit for the relay 16': battery, winding of 16', T112, R161, R123 and earth. The relay 16' closes at T161' its holding circuit to earth at T12.

15 The following circuit for the lower winding of the relay 16 is established: battery, lower winding of relay 16, T162', wiper c in position 1 and earth. When the relay 16 operates, the circuit of the 25 stepping magnet Cm1 is established and the return impulse coming from the exchange B is received in the exchange A, as already explained.

20 When the make and break switch reaches position 11, relay 16 drops, its circuit being open in 30 the wiper e.

The make and break switch again steps and a long impulse is transmitted from A to B, as in the previous case.

When the operator at B replies, a short impulse 35 is sent from B to A, and thus, as in the previous case when the called subscriber replies, operates the relays 2, 11, 4, 15 and 15', and extinguishes the supervisory lamp of the operator's cord circuit at A.

40 Before 15' drops, relay 14 is energized in the following circuit: battery, winding of 14, T163', T152', R153 and earth. When relay 15' drops, relay 14 is energized in series with 14' over T141, and earth at T12. The relay 14' is energized in 45 this circuit.

The two operators are now connected and may route the waiting call.

When the call has been completed and the 50 called operator at the B exchange replies, a short impulse (say 100 milliseconds) is sent from B to A and received on relay 2 (Fig. 1).

55 Relays 2, 11 and 4 thus operate, as has already been shown. A circuit for the relay 13 is completed over: battery, winding of 13, T141', T41 and earth.

The alternating current of G1 is sent via T131 and T132 to the relay at the end of the cord circuit (not shown) which energizes and lights up the indicator lamp.

60 If the operator at the exchange A is calling by depressing her calling key, then relays 2 and 11 will be energized, as already shown. The following circuit is closed for the relay 8: battery, winding of 8, T142', R62, T115, R41 and earth. The relay 9 is energized by T81 and an A. C. impulse is sent to the exchange B over T91 and T92. The duration of this impulse corresponds to the time during which the retarded relay 6 is held whose circuit is closed at T21. The period during which this relay is held is increased by introducing a high resistance R3 in its circuit. When 6 energizes, it opens the circuit of relay 8 at R62, which drops and opens the circuit of relay 9, which also drops. The transmission of the impulse is completed even though the operator at A continues to

press her calling key, since relay 2 and consequently relay 6, remain energized while this key is depressed.

If the operator of exchange B removes the plug, the same signal is given as in case of a call and, moreover, a busy signal is sent over the line.

When the operator at exchange A removes the plug, the release of the mechanism in Fig. 1 takes place as previously described. When the relay 12 drops, it opens at T121 the circuit of relays 14, 10 14' and 16, which drop.

In the case where the calling operator at exchange A pulls out the plug before depressing the dial key, or the calling key, relay 1 drops, and relay 16 is energized over its lower winding through R11, the wiper e in positions 1 to 10 and earth. The circuit of the magnet Cm_1 is closed, as has already been shown at T163, and the make and break switch will step eleven steps, sending a long impulse to exchange B.

Two conditions may arise:

(1) The return impulse from exchange B is not received at exchange A. In this event, relays 15, 15' and 12 are not energized. The make and break switch returns to rest position via R151, 25 the wiper (b) of the switch in position 11, and over R121 and the wiper (f) of the switch in positions 12 to 21.

(2) The return impulse from exchange B is received at exchange A. In this event, the relays 15 and 15' are energized over T152, R12, R11, wiper e of the make and break switch in positions 1 to 10, and earth. The relay 12 is energized over T154' and held over T122.

The stepping circuit of the switch is established in position 11 by: earth, R13, T151, wiper b of the switch in position, contact and winding of the magnet, Cm_1 and battery.

The relay 16 is energized over R12, T121 and earth.

From the moment when the make and break switch advances from position 11, a long impulse is sent from exchange A to exchange B, as has been shown when the operator releases her dialling key in the case where a subscriber is called from exchange B by the operator at A. This impulse is followed by another long impulse which effects the release.

In the event that the operator at A pulls out the plug after having depressed her dialling key, or during dialling, then the release will take place in the same way as in the last case considered.

The operation of the input or impulse repeating mechanism will now be described with reference to Fig. 2. This mechanism is equipped to function in conjunction with a recorder such as that shown in Fig. 3. It routes the calls either towards an automatic switchboard or towards a group of operators' ringing relays (Fig. 4).

Assuming that a call emanating from exchange A is received at exchange B, when the operator at exchange A plugs into the jack of a disengaged toll circuit, a long impulse (say, for example, 700 milliseconds) is sent from A to B, as has already been explained. This impulse is received by relay 2 (Fig. 2) over the conductor L1 (Fig. 1), R132', conductor A, R124 (Fig. 2), R172', R183, R165, winding of relay 2, R181', R172, conductor B, R131' (Fig. 2) and line conductor L2.

At R21, the relay 2 opens the following circuit of the relay 3 which drops: battery, winding of 3, R41, R51, R21 and earth. The outgoing equipment (Fig. 1) associated with the input mechanism of Fig. 2, is made busy in consequence of the opening at T32 (Fig. 2) of the circuit of its

75 relay 3 (Fig. 1), as has already been explained. The relay 5 is energized in the circuit: earth, R31, upper winding of 5, resistance R2 and battery.

When the impulse from the exchange A is completed, the relay 2 drops and the relay 1 is energized via: earth, R21, T51, resistance R4, winding of 1 and battery. The relay 4 is energized by the earth at T11 and the relay 15 over that of T45. At T52, the starting circuit of the generator G2 is completed. The starting circuit which operates the register finders Co3 (Fig. 3) is completed over: starter wire, MM, R34, R141, T45 and earth.

15 When the wipers of one of the disengaged register finders reaches the bank contacts to which the mechanism shown in Fig. 2 is connected, the circuit for the relay which stops the finder is established via: battery, resistance R5, T42, R35, R16 and wire p towards the finder bank contact.

20 The finder stops, as will be explained later, and battery is applied through the register finder to the wire q. The relay 16 is energized in the circuit: battery, on wire q, relay 16, R144, T45 and earth. The relay 14 is energized by battery winding of 14, T164, T45 and earth. The holding circuit of the relay 16 is closed via: T166, R206', T45 and earth; and that of the relay 14 via T144, T45 and earth.

30 The relay 11 is energized in the following circuit: battery, resistance R6, winding of 11, R191', R61, T141, T45 and earth. The relay 1 12, T111, T112, R191', R61, T141, T45 and earth. The relay 19 is energized via: battery, upper winding of 19, R192', T123, T112, R191', R61, T141, T45 and earth.

35 The relay 11, whose winding is short-circuited by T112 and T125, drops. After 11 has dropped and has thus opened T112, the relay 19' is energized and 19' is held in the following circuit: battery, upper winding of 19 and 19', T191, T45 and earth.

40 The circuit of the relay 12 is opened at T112, but this relay, whose winding is short-circuited by T126 and R111, is retarded in release and drops only after a little while. While the relay 11 is attracted, a short A. C. impulse (say 100 milliseconds) is transmitted by T124 and T121 over the line conductors from the exchange A to the exchange B.

45 The following starter circuit for the preselector Co2 is established: battery, magnet Cm_2 of Co2, T142, T143, R101, R205, wiper T1 of Co2 and earth on the bank contacts corresponding to the junction lines leading to the engaged automatic switch. When the wipers of Co2 arrive on a disengaged junction line, then the wiper T1 will not find an earth and relay 10 is energized in the following circuit: earth, R205, winding of 10, T142, Cm_2 and battery.

50 The relay 10 opens at R101 the stepping circuit of the preselector. At T101, it applies on earth to the bank contact to mark the junction line engaged.

55 When the operator at the exchange A dials the called number, A. C. dialling impulses will be sent from A to B.

60 In the input equipment of Fig. 2, these impulses are received in the relay 2 through the circuit: conductor L1 (Fig. 1), R132', conductor A, R124 (Fig. 2), R172', R183, resistance R3, relay 2, R181', R172, R121, conductor B, R131' (Fig. 1), conductor L2.

75 The impulses received by relay 2 are repeated

by the relay 1 whose circuit is cut at R21 at each attraction of 2. They are retransmitted to the register (Fig. 3), via: battery, R8, R12, T162 and wire r.

The re-transmission of the impulses by the register takes place over the following circuit: conductor A of preselector Co2, T105, T163, wire t, impulse cam of register, wire u, T161, T102, wiper b of Co2.

When dialling has been completed and the operator at the exchange A has released her dialling key, a long impulse is sent from A to B, as has already been explained, to operate relay 2. At R21, the relay 2 opens the circuit of the relay 1, which drops. The battery through the resistance R8 is applied via R12 and R162 to the wire r of the register.

When the register has completed the re-transmission of the called number, the circuit of relay 18 is opened in wire q, and this relay drops. The register is released, as will be explained below.

The relay 9 is energized in series with the feed relay of the junction line through the following circuit: wiper a of Co2, T105, R183, R203', left-hand winding of the relay 7, lower winding of relay 9, R201', R161, T102 and wiper b of Co2.

The relay 7 whose right-hand winding is fed by R206' and T45, is not energized on account of the direction of the current in its left-hand winding. When the called subscriber replies, the direction of the current is reversed in the left-hand winding of 7, and this relay operates and at T71 it closes the circuit of the relay 6 which energizes.

The relay 11 and, consequently, the relay 12 are energized in the following circuit: T191', T61, T141, T45 and earth. The lower winding of relay 19 is fed via: battery, lower winding of 19, T192', T123, T112, T191', T61, T141, T45 and earth. The flux created by this winding causes the relay 19 to drop.

The relay 19' remains up and relays 11—12 drop, as has been shown in the foregoing. During the time that the relay 12 is held, a short A. C. impulse is transmitted to exchange B.

When the relay 12 has dropped again, the relay 19 drops, its circuit being opened at T123.

The speech circuit is completed via: conductor L1 (Fig. 1), R132', conductor A, R124 (Fig. 2), R172', condenser C2, R163, T105, wiper a of Co2, automatic switchboard equipment, line and station of called subscriber, wiper b of Co2, T102, R161, condenser C3, R172, conductor B, R131' (Fig. 1) and conductor L2.

At the close of the conversation, when the called subscriber replaces his receiver, current will flow again in the left-hand winding of relay 7 and the relay drops, opening at T71 the circuit of relay 6, which also drops.

The circuit of relays 11 and 12 is again closed and these relays in common with relays 19 and 19', operate. While relay 12 is held, a monitoring impulse is transmitted from the exchange B to the exchange A to indicate to the operator at exchange A that the called subscriber has replaced his receiver.

When the operator at exchange A removes the plug, a long impulse is sent to exchange B and is there received on the relay 2 (Fig. 2). At R21, the relay 2 opens the circuit of the relay 1, which drops.

Relay 5 drops again, its upper winding being short-circuited via: earth, R11, T44 and R167.

When the impulse from A is received, and relay 2 drops, relay 4 is short-circuited via: earth, R21, R51 and T41. When relay 4 drops, it opens at

T45 the circuit of relays 19, 19', 15, 14, 20 and if necessary 20'. The relay 10 drops, its circuit being opened at T142.

The incoming mechanism is freed. The relay 5 is held by R41 and R21 and at T32 closes the circuit of relay 3 of the outgoing mechanism to operate the disengaged indicator lamps.

In the case where the operator of exchange A calls the operator of exchange B, the operations previously indicated in the case of the call from the subscriber takes place until such time as the preselector Co2 stops on a disengaged junction line leading towards the automatic switchboard.

The operator at exchange A then operates her calling key, and thus, as has already been explained, transmits a long A. C. impulse from A to B.

This impulse is received on relay 2 (Fig. 2), relay 1 drops, its circuit being opened at R21. At the end of the impulse, relay 2 drops again. At this point a battery is applied in the register to the wire r, as will be explained below. The following circuit for the relay 20 is closed: earth, lower winding of 20, T12, T162 and battery on the wire r. The relay 20 opens at R205 the circuit of relay 10, which drops. The following circuit for relay 9 is established: battery, upper winding of 9, T206, R104 and earth. The relay 23', which is no longer short-circuited at R92, is then energized, and is held in series with the upper winding of the relay 20 by T204, T45 and earth.

The circuit for starting up the preselector Co2 is established via: battery, electromagnet Cm2, contact of the electromagnet, T142, T143, R101, T205', wiper T2 and earth on the corresponding bank contacts to the junction lines leading to the automatic switchboard. All the bank contacts associated with the wiper T2 are connected to earth for all the positions which correspond to the junction lines leading to the automatic switchboard.

The wipers Co2 advance, therefore, over all the contacts of the junction lines to the automatic switchboard and over the bank contacts corresponding to the disengaged lines, and arrive on the bank contacts of the junction lines leading to the groups of operator calling relays. An earth is applied to the terminal corresponding to wiper T2 for all the engaged lines. When the wipers of Co2 reach a disengaged line, the earth on the wiper T2 is removed and the relay 10 is re-energized via: earth, T204', relay 10, T142, contact of the magnet Cm2 and battery. Relay 10 opens at R101 the stepping circuit of Co2, and at T101 applies earth to the wiper T2 to hold the line.

When the operator at exchange B replies, the wiper T1 is earthed, as will be explained in what follows, and via T202' and T103' closes the circuit for the relay 6, which is energized.

Relays 11, 12, 19 and 19' operate in the same way as when the called subscriber answers. A short monitoring impulse is transmitted from B to A to inform the operator at A that the operator at B has answered.

The speech circuit is set up via: conductor L1, R132' (Fig. 2), conductor A, R124, (Fig. 2), R172', T203', R163, T105, wiper a, operator's station via the relay group (Fig. 4), wiper b of Co2, T102, R161, T201', R172, R121, conductor B, R131' (Fig. 1), conductor L2.

On the completion of the dialling, when the operator at B removes the plug, earth is cut off the wiper T1 of Co2, as will be explained in what follows, and the relay 6 drops, causing relays 11,

12, 9 and 19' to operate, as before, and transmits to the exchange A a monitoring impulse. Then the mechanism is released on the reception of the release impulse coming from A, as in the case of a call from a subscriber at B via the operator at exchange A.

When a communication has been established between the switchboards of the operators at A and B, and the operator at A, whom we are assuming to be the outgoing operator, makes a call by operating her calling key, a short impulse is transmitted from the exchange A to the exchange B, and is received on the relay 2 (Fig. 2) through the circuit: conductor L₁, R132' (Fig. 1), conductor A; R124, R172', R183, R165, relay 2, R181', 15 R172, R121, conductor B, R131' (Fig. 1) and conductor L₂.

At R21, the relay 2 opens the circuit of the relay 1 which drops. The following circuit for relay 17 is closed: earth, lower winding of 17, 20 T202, R12; resistance R5 and battery. The relay 2, whose circuit is opened at R172 and R172' drops, the relay 17 is held by its upper winding over T171 and T152. The following circuit of the relay 18 is closed: lower winding of 18, T171', 25 T151, R21 and earth.

Before the completion of the impulse, the relay 2 is re-energized in the following circuit: conductor L₁, R132 (Fig. 1), wire A, R124 (Fig. 2), 30 T46, T183, R165, winding of 2, T181', R121, conductor B, R131' (Fig. 1) and conductor L₂. The relay 15 is short-circuited at T175 and drops again. The relay 17 is maintained on its lower winding over T202, R12, resistance R8 and battery. The relay 18 is maintained on its upper winding over T181, T171 and earth.

An alternating current impulse is transmitted to the relay group of Fig. 4 via: generator G₂, T113, T182', T203', R163, T105, wiper a and bank contact, equipment of Fig. 4, wiper b, T102, R161, T201', T182, T173', and generator G₂.

When the impulse from exchange A has been received, the relay 2 drops, and the relay 1 is re-energized. The relay 17 drops, its holding circuit being open at R12. At T171, it opens the circuit of 18, which drops. Relay 15, which is no longer short-circuited at T175, is again operated.

The impulse transmitted to the equipment of Fig. 4 is completed, the transmission circuit being opened at T173 and T173'.

Where, in the course of a conversation, the incoming operator in exchange B calls, a short impulse is transmitted by the equipment of Fig. 4 (as will be explained in what follows) and is received in Fig. 2 via: bank contact and wiper a, T105, R163, T203', T105, R163, T203', T105, R163, T203', R183, R165, winding of 2, R181', T201', R161, T102, wiper b and bank contact. The relay 2 opens the circuit of relay 1, which drops. The circuit of the lower winding of relay 17 is completed at R12 and this relay at T173 short-circuits relay 15, which drops.

A short alternating current impulse is transmitted to the exchange B via: generator G₂, T113, R182', T46, R124, conductor A, R132' (Fig. 1), conductor L₂, apparatus of Fig. 1 of exchange A, conductor L₂, R131', conductor B, R121 (Fig. 2), R182, T173, generator G₂.

This impulse is received on the equipment of Fig. 1 at the exchange A, and as already explained, signals the operator.

When the reception of the impulse in Fig. 4 has been completed, relay 2 (Fig. 2) drops. The relay 1 is re-energized. The relay 17 drops and 70 75

the relay 15 is re-energized. The transmission of the impulse to the exchange A is completed.

If an input equipment is inadvertently seized, it immediately engages the corresponding outgoing equipment. A recorder is connected and a short return impulse is sent. This short impulse cannot cause the incoming equipment at the distant exchange to be connected.

Two cases can arise:

(1) The outgoing equipment of the distant exchange which is not engaged is, nevertheless, seized by an operator. The repetition of the impulse sent by the distant exchange will cause the release of the recorder (impulse operating as upon the completion of dialling), the release of the circuit, and finally the normal connection of the circuit.

(2) The outgoing circuit remains disengaged. After a certain lapse of time, an earth will be applied in the register (as will be explained in what follows) to the wiper L, and will, through the wire s short-circuit via T145 (Fig. 2) the relay 5. The relay 5 drops and opens at T51 the circuit of 1 which drops and short-circuits via R21, R51 and T41 the relay 4, which also drops.

The release is then effected as before. The release of the register occurs after the opening of T45 and the circuit of the maintenance relay is opened in the line q and the wiper M.

We shall now describe, with reference to Fig. 3, the operation of the register which is provided to operate in conjunction with the incoming equipment to insure the correct re-transmission of the dial impulses to the automatic switchboard of the incoming exchange.

It has been explained in connection with the operation of the incoming equipment of Fig. 2 that when said equipment is contacted, earth is applied to the starter wire MM of the registers.

The following circuit is completed for each free register: earth on wire MM, wiper ff of Co4 in position 0, Fig. 3, wiper fb of Co5 in position 0, R126, upper winding of relay 7 and battery. Relay 7 completes the following circuit for the magnet Cm3 of the register finder Co3: battery, magnet Cm3 and its contact, T71, R61, R21 and earth.

When the wipers of Co3 reach the terminals of the input equipment in use, the following circuit for relay C is completed: earth, R21, T73, lower and upper windings of 6, wiper T, wire p and battery via the apparatus of Fig. 2.

At R61, the relay 6 opens the stepping circuit of the magnet Co3 which stops. At T62, it completes the circuit of the lower winding of the relay 7 in parallel with the lower winding of 6. The two windings of relay 7 being in opposition, its armature drops. The circuit of the upper winding of the relay 12 is completed as follows: earth, T63, R72. The relay 6 is held by T61.

The circuit of relay 12 is completed over its lower winding via: battery, lower winding of 12, R21, T125, wiper M and earth on the wire q through the incoming equipment.

The relay 6 drops, the battery being disconnected from the wire p in the input equipment. The following circuit of relay 2 is completed: battery, resistance R10, winding of 2, R53, T124, R13, R62 and earth.

The register (Fig. 3) is now connected with the incoming equipment (Fig. 2) and the transmission signal is sent to the calling exchange via: R51, T122', wiper IE, wire r and through the incoming equipment.

When the outgoing operator dials the called

number, alternating current impulses are received on the incoming equipment (Fig. 2) and are retransmitted on the wire r of the wiper IE of Co3 (Fig. 3). At each impulse, the relay is energized in the following circuit: battery on the wire r in the incoming equipment, wiper IE, T122', winding of 1, R41, R111, T121 and earth.

The circuit of the relay 4 is established: battery, winding of 4, T12, T123' and earth. The relay 1 is maintained by T11. When relay 1 drops again the relay 4 is maintained by T42, T121', contact of the electromagnet Cm4 and earth. After the relay 1 has been released, the relay 3 is energized in the following circuit of its upper winding: battery, upper winding of 3, R32, T23, T43, T25, R12, T123' and earth. The relay 3 sticks, and via T33 completes the following circuit of the relay 5: battery, winding of 5, T33, T121 and earth. The relay 5 is held and via T52 closes its holding circuit.

The circuit for the magnet Cm4 of the contactor Co4 is closed as follows: battery, magnet Cm4, T32, T23, T43, T25, R12, T123' and earth. The magnet Cm4 attracts its armature and opens the circuit of the relay 4 which drops again. The relay 4 reverts to non-operating condition, opens at T43 the circuit of the magnet Cm4 which releases its armature, thus causing the wiper of Co4 to advance by one step.

When, under the action of the following impulses, the relay 1 pulls up, the relay 4 is re-energized at T12 and completes the circuit of the magnet Cm4 which attracts its armature, opens the circuit of relay 4 which drops again, and thus causes a new advance by one step of the wipers of Co4.

The same operations are repeated for each dial impulse received on the relay 1, causing the advance of the wipers of the switch Co4 by one step.

The relay 3 is held for the duration of each series of impulses by T31, its lower winding being short-circuited by R11 and R41. A moment after the end of each impulse series, the relay 3 drops. The charging circuit of the condenser which is connected to the bank contact of the wiper d of Co4 and on which said wiper is stopped at the end of the impulse series, runs through: battery, parallel winding of the relay 21, T125', R34, wiper d , condenser, resistance R11 and battery.

The same operations are repeated for each series of impulses, as many condensers being connected to the bank contacts of the wiper d as there are digits in the number received.

The re-transmission of the impulses will now be explained.

The selector of the automatic switchboard is connected with the register through the incoming equipment over the following fundamental circuit loop: wire t , wiper A, T122, R252, T123, wiper B, wire q . Relay 9 is energized by its upper winding over R92 and this loop and locks up over its lower winding and T91 to the earth at T121.

When the first digit has been registered, the following circuit of relay 24 is closed: battery, resistance R12, winding of 24, R231, T93, R212, T54 and earth. The relay 24 closes the following circuit for relay 26: battery, winding of 26, T242, R231, T93, R212, T54 and earth.

Relay 24 is short-circuited at T262 and drops. Relay 26 is held by T263. The energizing circuit of the relay 28 is closed at T261 and R243. When cam K2 is opened, the circuit of relay 25 is completed through: battery, series winding of 25, T282, R221, T283 and earth. The stepping circuit of the magnet Cm5 is established through: battery,

magnet Cm5 of Co5, T251, cam K2, T282, R221, T283 and earth.

At R252, the cam K1 is disconnected and introduced into the above traced circuit of the selector. 5 When the cam is opened, an impulse is transmitted to cause the selector to operate.

When the wipers of Co5 reach the bank contacts which correspond to the bank contacts of Co4, on which the wipers are first stopped, the 10 condenser which has been charged is discharged through the wiper a and the winding of the relay 22. This relay is energized and locks up over T221 and earth at T283.

The circuit of the magnet Cm5 is opened at 15 R221 and the switch Co5 is stopped. The relay 25 is held and the relay 23 is energized over the following common circuit: battery, series winding of 25, T282, winding of 23, T283 and earth.

The cam K1 is short-circuited at T232 and the 20 circuit of relay 26 is opened at R231. When the relay 26 drops again, the relay 28 drops in its turn, its circuit being opened at T261. At T283, relay 28 opens the circuit of relays 22, 23 and 25, which drop.

25 It will be seen that the same number of interruptions are produced in the fundamental circuit as there were impulses in the first digit of the number received on the switch Co4. The wipers of Co5 have been stopped in the position which corresponds to the first position in which the wipers of Co4 stopped.

The registering and re-transmission of the other digits of the called subscriber's number takes place in the same manner.

30 35 When the operator at the outgoing exchange has completed dialling, she opens her dialling key and a long impulse is transmitted to the incoming exchange. This impulse is received in the incoming apparatus and causes relays 1 and 4 of the register to be attracted (Fig. 3). The relay 2 drops. When reception of the impulse has been completed, relay 1 drops, but relay 2 cannot again energize, its circuit being opened at R53.

When the last digit has been re-transmitted, 45 40 the wipers of Co5 will have caught up those of Co4, whereupon the relay 21 will be energized in series with 22 in the circuit: T125', R34, wiper d of Co4, wiper a of Co5. At R211, the relay 21

50 opens the circuit of the relay 12 which includes wire q and wiper M of Co3. The relay 12 drops, and at T121' opens the circuit of the relay 4, and at T125', the circuit of relays 21 and 22, which drop.

The following circuit is closed for the return 55 to rest position of the switch Co4: battery, magnet Cm4, wiper ff on the sectors f , R121', contact of magnet Cm4 and earth. When the wipers of Co4 reach position 0, the circuit is opened.

The switch Co5 returns to rest position via the 60 circuit: battery, magnet Cm5 and its contact, sectors b and wiper fb , R121 and earth.

In the event that the operator at the outgoing exchange wishes to communicate with the operator at the incoming exchange, the same connecting operations take place that have been previously indicated, and an idle register is connected with the incoming equipment.

However, instead of operating her dialling key, the operator of the outgoing exchange operates her calling key, and a long A. C. impulse is transmitted to the incoming exchange. This connects battery to the wire r , as has already been explained before. The following circuit for relay 1 (Fig. 3) is closed: battery, on the wire r , wiper IE, T122', winding of 1, R41, R111, T121 and

earth. At T₁₁, the relay 1 closes its holding circuit. At T₁₂, it closes the energizing circuit of relay 4: battery, winding of 4, T₁₂, T₁₂₃' and earth.

Relay 2 is short-circuited by T₁₃ and R₆₂ drops, and relay 12 is held by R₂₁₁. The following circuit of relay 11 is closed: battery, winding of 11, R₂₃, T₄₃, R₂₅ and earth.

When the impulse has been received, relay 1 drops again, battery being cut off the wire r in the incoming apparatus. Relay 4 is held by T₄₂, T₁₂₁', contact of the magnet C_{m4} and earth. Relay 2, which is no longer short-circuited at T₁₃, is re-energized, and relay 11 is held over T₁₁₁, T₁₂₁ and earth.

Battery is then applied to the wire r through: battery, resistance R₁₃, R₅₅, T₁₁₂, T₂₆, T₁₂₂', wiper IE of C_{o3} and wire r. This battery in the input apparatus, as has already been described, causes the orientation of the preselector C_{o2} (Fig. 2) on to a disengaged operator's position.

The holding circuit of relay 12 is opened in the incoming equipment on the wire p, and the relay drops again opening at T₁₂₁, the circuit of 4 which opens at T₁₂₁ the circuit of 11, which also drops. Relay 2 drops again, its circuit being opened at T₁₂₁ and T₁₂₄.

When the register (Fig. 3) is connected, relay 27 is energized through: battery, upper winding of 27, T₁₂₆' and earth through cam 1, while said cam is closed. This relay 27 is then held attracted on its lower winding through: battery, lower winding of 27, T₂₇₂, R₂₄₁, R₃₃, T₁₂₁ and earth. If the dialling is then carried out normally the holding circuit is cut at R₃₃ or R₂₄₁ and the relay 27 drops. If, on the other hand, the dialling is not carried out, or if the time which elapses between the reception of two successive series of impulses is too long, then after a certain time (depending on the cams) the relay 27' is energized, when the cam 2 operates through T₂₇₁ and its upper winding. It is held on its lower winding by T₂₇₁', T₁₂₁ and earth. Via T₁₂₁ and T₂₇₂' earth is then applied through the wiper L of C_{o3} to the wire s, which causes in the input apparatus, as already described, the holding circuit of the relay 12 to be cut off the wire 2 and, consequently, the release of the register.

We shall now describe with reference to Fig. 4 the operation of the group of relays by means of which the calls intended for the incoming operator are routed from the incoming apparatus.

When, as has already been explained, a pre-selector such as C_{o2} (Fig. 2) stops in the position corresponding to the group of calling relays of Fig. 4, earth is applied to the wiper T₂ and the corresponding bank contact. The circuit of relay 7 is completed over R₇₁', and this relay completes at T₇₃ the circuit of the calling lamp LA of the operator.

The return signal from the called subscriber's is sent via T₇₂, R₈₂', bank contact and wiper A and via T₇₁, R₈₂, bank contact and wiper B.

The operator advised of the call by the lighting of lamp LA plugs one of her cord circuits into the jack J₄. The circuit of the relay 6 is closed at R₇₃' to earth applied to the sleeve of the jack J₄ through the cord circuit. The relay 6 closes via T₆₇ and T₆₆ the circuit of the relay 7' to earth on wire T₂. When relay 7' energizes the relay 6 is held over T₆₄. The relay 7 whose circuit is opened at R₇₁', drops. At T₆₃, relay 6 completes the circuit of relay 1, which operates.

Through T₆₂, earth is applied to bank con-

tact and wiper T₂ to control in the incoming equipment the supervision of the call.

The connection is established over the wiper and bank contact A, R₈₂', tip of the jack, cord circuit and station of the operator, ring of the jack, R₈₂, bank contact and wiper B.

When, in the course of a call, the incoming operator wishes to call the outgoing operator, she operates her dialling key. The circuit of relay 2 is closed via the tip of the jack J₄, R₄₃, relay 2, R₄₂ and ring of the jack J₄. At T₂₁, relay 2 completes the circuit of relay 8 which operates.

An A. C. impulse is transmitted to the incoming equipment (Fig. 2) in order, as has already been explained, to cause transmission of an A. C. impulse to the outgoing exchange: generator G₅, T₆₃', R₃₂, R₄₄, T₆₅, T₇₄', bank contact and wiper A, incoming apparatus, wiper and bank contact B, R₄₆, R₃₁, T₈₃, generator G₅. The duration of this impulse is fixed by the time required for the attraction of the relay 3 whose circuit has been closed at T₈₄' and R₄₅. As soon as the relay 3 is energized, the impulse terminates, the transmission circuit being opened at R₃₁ and R₃₂.

The purpose of this arrangement is the sending of a short impulse to the outgoing exchange, irrespective of the length of time it takes the operator to manipulate the dial.

The relay 1 which is short-circuited via earth, T₆₃ and T₈₄, drops again. When the operator releases the dial, the relay 2 drops, opening at T₂₁ the circuit of the relay 8, which also drops. The relay 1 which is no longer short-circuited at T₈₄, is energized again. The relay 3 drops again, its circuit being opened at T₈₄'.

The line is released before the relay 8 has dropped completely, via the following short circuit: wiper and bank contact A, T₇₄', T₆₅, R₄₄, R₃₂, R₈₅', R₁₃, R₄₆, bank contact and wiper B.

When, in the course of the call the outgoing operator calls the incoming operator, a short A. C. impulse energizes the relay 2 in the following circuit: wiper and bank contact A, R₈₂', R₄₃, winding of 2, R₄₂, R₈₂, bank contact and wiper A. Relay 2 closes via T₂₁ the circuit of relay 8, which at R₈₂ and R₈₂' opens the circuit of 2. The relay 8 is held at T₁₁ and earth on T₈₁. The following circuit of the relay 4 is closed: battery, upper winding of 4, T₈₁', T₁₂, R₂₁ and earth.

During reception when the impulse has been completed, relay 2 is re-energized in the following circuit: wiper and contact A, T₇₄', T₆₅, T₄₃, winding of 2, T₄₂, bank contact and wiper B.

Relay 1, short-circuited at T₈₄, drops again. Relay 8 is held at T₂₁. Relay 4 is held at T₄₁ and T₈₁.

An A. C. impulse is transmitted to the operator's cord circuit via: generator G₅, T₆₃', R₃₂, T₄₄, tip of the jack J₄, cord circuit, ring of the jack J₄, T₄₆, R₃₁, T₈₃ and generator G₅. This impulse energizes the relay at the end of the cord circuit and thus lights up the terminating lamp in order to inform the operator of the call.

When the impulse has been received, relay 2 drops, opening at T₂₁ the circuit of relay 8, which also drops, opening at T₈₁ the circuit of 4, which drops.

The re-energization of relay 1 and the release of the line take place in the manner already described.

When, upon the completion of a call, the outgoing operator removes the plug, the impulse

75

received on the incoming equipment causes the release of the equipment and the earth will be removed from the wiper and contact T2.

Relay 5, short-circuited at T66, is then energized in series with the relay 7' which is held at T67. Relay 5 completes via T54 and T63 the holding circuit of its lower winding. Earth is applied to the bank contact and wiper T2 at T51 and T66, in order to insure continued holding of the group of relays in the banks of the preselectors.

The relay 7' is held at T67 and T51. The busy signal is sent to the incoming operator via T53, R82', tip of jack J4, cord circuit and operator's station, ring of J4, R82 and T52.

When the incoming operator removes the plug, relay 6 drops again, its circuit being opened in the sleeve of the jack J4. At T63, the relay 6 opens the circuit of relays 1 and 5, which drop. At T51, relay 5 opens the circuit of the relay 7', which drops.

If the operator at the incoming end is the first to unplug, then the relay 6 will drop after this cut-off operation has taken place, its circuit being opened in the sleeve of the jack.

The relay 7 is held via T71' and earth on the terminal and wiper T2. The incoming equipment transmits an impulse by cutting off earth at T62 from contact and wiper T1.

The busy signal is sent to the calling end via: R65, T74', contact and wiper A and via R61, T72' and contact and wiper B.

When the incoming equipment is released, the earth is cut off contact and wiper T2, and the relay 7' drops again.

If the toll boards of an exchange are so equipped that the operation of the dial does not operate switches in the outgoing equipment of Fig. 1, the outgoing equipment of Fig. 5 will be substituted.

This equipment comprises two make and break switches, driven successively by the magnets Cm1 and Cm2. The wipers of the make and break switch Cm1 are designated by capital letters and those of the switch Cm2, by small letters. Thus 0(A) indicates that this contact is closed by the wiper A of the make and break switch CM1 in position 0, and o(a) that this contact is closed by the wiper a of CM2 in position o.

The switch CM1 receives locally the first series of impulses which determines the total number of impulses to be sent by the operator. As soon as the impulses have been transmitted, the outgoing equipment will automatically send to the incoming exchange, a long impulse indicating the completion of dialling. This replaces the impulse which was sent in Fig. 1 when the operator released her dialling key.

When the equipment is free, relay 5' is energized in the following circuit: battery, winding of 5, wiper (a) of the switch and CM2 in the position o, wire c and earth through 1', incoming equipment. The circuit of the disengaged lamp In is closed at T52.

After having insured that the equipment is disengaged while operating the lighting up lever Lr, the operator plugs one of her cord circuits into the jack J1. The following circuit of relay 3 is then closed: battery, series winding of 3, R125, T51 and earth on the sleeve of jack J1 through the relay of the third wire of the cord circuit whose indicator lamp has been extinguished. At T31, relay 3 completes the circuit of relay 4 through the resistance R1. Relay 4 closes

its holding circuit via T42 and at T43 completes the circuit of relay 25, which is energized. At R251 and R252, relay 5 disconnects the outgoing equipment of Fig. 5 from the incoming equipment of Fig. 2.

The following circuit of magnet CM2 of the first switch is closed: battery, magnet cm2 and its contact, wiper (c) of switch cm2 in the position o, T32 and earth.

10 The switch cm2 advances by one step. Relay 5 drops again, its circuit being opened at the wiper a, which has left position o. Relay 3 is operated via T44. The following energizing circuit for relay 6 is then closed: battery, lower winding of 6, wiper e in position 1 and earth. At T61, relay 6 completes the following circuit of relay 21: battery, winding of 21, resistance R2, T61, wiper a in position 1 and earth. At T213, relay 21 completes the circuit of relay 23.

20 A long holding impulse of alternating current is transmitted in the holding circuit via: generator G, T212, T252, conductor L1, and G, T211, T251 and conductor L2.

The stepping circuit of switch cm2 is completed 25 via: battery, magnet cm2, T62, wiper c in position 1, interrupter Cm1 and earth. The switch cm2 advances step by step and the impulse is continuously transmitted over the inter-urban circuit.

30 When the switch cm2 arrives in position 5, the circuit of relay 1, through wiper a is opened. This relay falls off and at T212 and T211, opens the impulse circuit ending the transmission of the impulse. The relay 23, short-circuited at R213

35 falls, but only a moment after the dropping of 21, which permits the release of the line by short-circuiting at T232.

The switch cm2 continues to advance in the circuit: battery, winding of cm2, T62, wiper c in

40 positions 5 to 10, cam Cm1 and earth. When the switch arrives in position 11, the circuit of relay 6 is opened. The make and break switch passes this position via the circuit: battery, winding of cm2, wiper b in position 11, R121' and earth. It then reaches its rest position via wiper (f) in the positions 12 to 20, and earth on R71.

The same cycle of operations is repeated and the long impulses (about 700 milliseconds, for example) are transmitted over the inter-urban circuit

50 to the called exchange, the successive impulses being separated by a fixed interval of time (about 1 second, for example), until a return impulse is received from the incoming equipment (about 100 milliseconds, for example) on

55 relay 22 via the circuit: conductor L1, T252, R212, R283, winding of 22, R281, R211, T251 and conductor L2. At T221, relay 22 completes the circuit of the lower winding of relay 28 which at T283 and T281, substitutes the relay 24 for relay

60 22. The relay 28 is held on its center winding via T241 and does not fall off during the substitution of the relay 24 for relay 22 because it is retarded by its upper winding, which is short-circuited at T284.

65 The following circuit of the relay 12' is then completed: battery, lower winding of 12', R122, R311, T241 and earth. At the end of the reception of the impulse, the relay 24 drops, but the relay 12' is held on the following circuit in series 70 with 12 which is energized: battery, lower winding of 12', lower winding of 12, T122' T43 and earth. At T127, relay 12 completes the circuit of relay 7, which is held through T72.

The stepping circuit of switch cm2 is open at 75 R121' and the switch is held in position 11.

The relay 6 is held on the earth through the wiper *f* in position 11. The relay 3 is held on its lower winding through T121, its upper winding which has a high resistance is short-circuited at R125 causing the lighting up of the supervisory lamps of each of the operator's dials in the well-known manner.

The operator presses the dialling key and proceeds to dial the number of the called subscriber. This opens the holding circuit of relay 3, which beats in the rhythm of the impulses. The stepping circuit of switch *cm1* is completed each time the relay 3 is released: battery, electromagnet CM1, T124, R33, R112, T71 and earth.

The impulses are re-transmitted by the relay 21 via the circuit: battery, winding of 21, resistance R2, T126, T63, wiper *d* in position 11, or wiper *a* in positions 6 to 10, R32 and earth. Through T211 and T212, the dialling impulses are repeated on the inter-urban circuit L1—L2 as alternating current impulses.

The first impulse which is received, energizes relay 23' via T213. This relay is held during each series of impulses, the short-circuit around its winding at R123 during the release of 23, retarding it sufficiently. Relay 23 drops off a moment after the completion of each impulse series.

It may be assumed that the called subscriber's number has five digits and that the first digit is 1. The make and break switch *cm1* advances by one step. When relay 23 drops, the following circuit of relay 11 is completed: battery, winding of 11, wiper A in position 1, R231, R112, T71 and earth. As soon as R112 opens, relay 11 is energized via R111', T113, wiper D in position 1, and earth. The switch *cm1* advances to position 11 via the following circuit: battery, winding of CM1 and its contact, R113', T115, wiper D in positions 1 to 10 and earth.

When switch *cm1* reaches position 11, it stops, its circuit being opened on the wiper D. Relay 11 is maintained in series with relay 11' which is energized in the circuit: battery, winding of 11, winding of 11', T111, T43 and earth.

If the first digit of the called number differs from 1 (four-digit number, for example) the switch *cm1* advances the same number of steps as there are digits in the number transmitted. In this case relay 8 is energized when relay 23 drops via the following circuit: battery, wiper A in position 2 to 10, R231, R112, T71 and earth. The said relay is held by T81 on the earth of T43. Relay 11 is energized in the circuit: battery, winding of 11, R111', T83, wiper D in positions 1 to 10 and earth. The advance of switch *cm1* to position 11 and the holding of relays 11 and 11' takes place, as in the case where the first digit dialled was 1.

Each digit following the first, advances switch *cm1* by one step, the circuit being completed every time relay 23 is held via the wiper C in positions 11 to 14 and earth.

After the second digit has been dialled, the following circuit of *cm2* is completed: battery, winding of *cm2*, wiper *b* in position 11, T123, T112' or T82, wiper B in position 15 or 14, wiper *f* in position 11 and earth. The make and break switch *cm2* advances by one step, and passes to position 12. The relay 6 is held via: battery, upper winding of 16, wiper *d* in position 12, T71 and earth.

The stepping circuit of the make and break switch *cm2* is completed via: battery, winding of *cm2*, T62, wiper *b* in positions 12 to 15, cam *Ca2* and earth.

The relay 21 is energized via: battery, winding of 21, resistance R2, T61, wiper *d* in positions 12 to 15, T71 and earth. At T213, relay 21 completes the circuit of relay 23 which operates. 5 The switch *cm2* is stepped by cam *Ca2*, and while it moves a long A. C. impulse is transmitted on the toll circuit via T212 and T211.

When switch *cm2* reaches position 16, the relay 6 drops, its circuit being opened in the wiper *d*. 10 At T61, it opens the circuit of 21, which drops and short-circuits at R213 relay 23, which drops after a short time.

If the called subscriber is engaged, the operator receives the busy signal. If the subscriber is free, she receives the ringing tone.

15 When the called subscriber answers, a short impulse is transmitted by the called subscriber's exchange to energize relay 22 which causes 23 and 24 to operate, as has already been explained, when the incoming equipment was connected.

20 The following circuit for the upper winding of the relay 12' is completed: battery, upper winding of 12', T123', T122, R311, T241 and earth. This winding being in opposition to the lower winding, relay 12' drops again. The relay 12 is held on its upper winding by T122, R311, T241 and earth.

25 When the impulse has been received, relay 24 drops again, and at T241 opens the holding circuit of relay 12. After the relay 12 has been released, the upper high resistance winding of the relay 3 is put back into circuit, which causes the supervisory lamp of the cord circuit to be energized in the known manner.

30 Communication between the two subscribers may now be established.

When the called subscriber replaces his receiver, a new short impulse is transmitted by the equipment of the incoming exchange to operate relay 22 which causes the operation of relays 28 and 24, and the re-energization of relays 12 and 12', as has already been mentioned. At R125, the upper high resistance winding of the relay 3 is cut out, which causes the cord circuit supervisory lamp to light up. The relay 3 is maintained on its lower winding by T121.

When the calling subscriber hangs up, the relay 3 drops, its circuit being opened in the third wire of the cord circuit. Relay 4 is maintained by T42. Relay 6 is re-energized in the following circuit: battery, lower winding of 6, wiper *d* in position 16, R32 and earth.

55 The following circuit for the operation of the switch *Cm2* is closed: battery, winding of *Cm2*, T62, wiper *b* in positions 16 to 18, cam *Ca1* and earth. Relay 21 is re-energized via: battery, winding of 21, resistance R2, T61, wiper *d* in positions 17 to 19, T71 and earth.

60 During the advance of switch *Cm2* to position 19, a long release impulse is transmitted to the called subscriber via T212 and T211.

When the switch reaches position 19, relay 7 falls, its circuit being open in wiper *b*. At T71, it opens the circuit of relays 6 and 21, which 65 drop. At R213, relay 21 short-circuits relay 23, which drops.

The switch advances to position 21 via: battery, winding of *Cm2* and its contact, wiper *f* in positions 12 to 20, R71 and earth.

70 Relay 4, short-circuited by R31 and wiper *b* in position 21, drops.

The switch *Cm2* returns to its rest position via R45 and the wiper *f* in position 21.

The relays 12, 12', 11, 11', 8 and 25 drop, their 75 circuit being opened at T43.

Relay 5 is re-energized through the incoming equipment via the wiper *a* in position 0.

When relay 4 drops, switch CM1 returns to the rest position by the circuit: battery, magnet CM1 and its contact, R113', R46, wiper *d* in positions 1 to 20 and earth.

We shall now describe the operation of the equipment of Fig. 5 when the operator at the calling exchange wishes to enter into communication with the operator of the called exchange.

The course of the operations after plugging into jack J1, the transmission of the holding impulse and the reception of the impulse in return, is the same as in the preceding case.

In order to call the operator at the called exchange, the operator at the calling exchange depresses her calling key. Relay 22 is energized by the calling current coming from the cord circuit via: tip of jack J1, R272, relay 22, R271, and ring of jack J1. The circuit of the lower winding of relay 28, and that of relay 26, is completed at T221, the circuit of relay 10 is completed: T263, R114 and earth, and this relay is held over T101.

The stepping of switch Cm2 via T62, the reception of the return impulse, and the energization of relays 12', 12 and 7 then take place in the same way as in the preceding case.

Position 11 of switch Cm2 is cleared by the circuit: battery, magnet cm2, wiper *b* in position 11, T123, T102, wiper *f* in position 11 and earth. The switch cm2 then advances to position 16, and a long impulse corresponding to the holding impulse of the dialling operation is transmitted to the called exchange, as in the preceding case. When the make and break switch was in position 11, the relay 31' was energized by the circuit: battery, winding of 31', T102, T102, wiper *f* in position 11 and earth. It is then held in series with 31 which is energized in the circuit: battery, winding of 13', winding of 31, T311', T43 and earth.

When the operator of the called exchange answers, a short impulse is transmitted and causes, as in the preceding case, when the called subscriber answers, the energization of relays 22, 28, 24, 12 and 12' and of the supervisory lamp in the cord circuit.

In case of a recall by the called operator, a short impulse is transmitted by the called exchange. This impulse causes the operation of relays 22, 28 and 24. The circuit of the relay 21 is then completed: battery, winding of 27, T311, T241 and earth. Via T271 and T272, the current of the generator G is transmitted to the end relay of the cord circuit plugged into J1 and causes the lighting up of the supervisory lamp so as to attract the attention of the operator of the outgoing exchange.

If the operator of the outgoing exchange recalls the relays 22 and 28 are energized when the operator manipulates her calling key. The following circuit of the relay 21 is then completed: battery, winding of 21, resistance R2, T312, R262, T221 and earth. At T213, relay 21 completes the circuit of the relay 23, which operates.

An A. C. impulse is transmitted on the toll circuit via T211 and T212. The duration of this impulse is determined by relay 26, which is energized over T221 and resistance R5, and a moment afterwards over T261. Relay 26 opens at R262 the circuit of relay 21 which drops and causes 23 to drop. The transmission of the impulse ends upon the release of relay 21 even if the operator continues to manipulate her calling key.

When the called operator unplugs, the signal is given as in the case of a call, but in this case the busy signal is transmitted to the outgoing exchange.

5 Release takes place after unplugging the jack J1, as in the previous case. Relays 31, 31' and 10 fall after the release of relay 4, their circuit being opened at T43.

In case the outgoing operator cuts off before dialling or operating her calling key, relay 3 drops. The relay 4 also drops, its winding being short-circuited at R31, wiper D in position 0 and earth. Relay 6 is energized on its lower winding by the wiper *e* in position 1, and earth. The switch cm2 advances to 11 and transmits the holding impulse.

Two cases may be considered:

(1) The return impulse is not received. In this case relays 12', 12 and 7 are not energized. The switch cm2 is released by the wiper *b* in position 11, and earth on R121', then by wiper *f* in positions 12 to 20 and R71, and finally by wiper *f* in position 21 and R45.

(2) The return impulse is received. In this case 25 relay 12 is energized, is held in series with 12 through T122', R41, wiper (c) in positions 1 to 10 and earth. Relay 7 is energized by T127 and is held by T72. The switch cm2 passes to position 1 via the circuit: battery, magnet cm2 and its contact, wiper *b* in position 11, T123, wiper A in position 0, R43 and earth. Relay 6 is held by T71, wiper *d* in positions 12 to 15, then by R32, wiper *d* in position 16 and, finally, by the wiper *d* in positions 17-19. A long impulse, as at the end 30 of the dialling, is transmitted to the outgoing exchange, then another long impulse for the release.

In the preceding description, it was assumed that each of the interconnected exchanges has an automatic switchboard. If an exchange that has no automatic switchboard is called an exchange like that shown in Figs. 1 or 5, then, as is shown by the dotted line in Fig. 7 for exchange A, the equipment of Fig. 2 is replaced by the equipment of Fig. 6.

We shall assume that exchange A is called by exchange B. When the operator of the exchange B seizes the circuit, an impulse is transmitted by the outgoing equipment. This impulse is received on relay 2 (Fig. 6), via the following circuit: conductor L1, R132' (Fig. 1), conductor A, R124, (Fig. 6), relay 2, R121, conductor B, R131' (Fig. 1), conductor L2.

55 Relay 3, which is normally held by R41, R51, R21 and earth, drops when its circuit is opened at R21. The outgoing equipment is engaged when the circuit of the wire C is opened at T32.

Relay 5 is energized on its upper winding by: earth, R31, upper winding of 5, resistance R1 and battery. When the impulse has been received, relay 2 drops and the circuit of the relay 1 is completed: battery, winding of 1, resistance R2, T51, R21 and earth. At T11, relay 1 completes the circuit of relay 4 which is energized. The following circuit of relay 11 is closed: resistance R3, winding of 11, R191', R61, T42 and earth.

70 Relay 12 is energized in the following circuit: battery, resistance R4, winding of 12, T111, T112, R191', R61, T42 and earth. The circuit of relay 19 is completed by: battery, upper winding of 19, R192', T123, T112, T191', R61, T42 and earth. Relay 11, short-circuited by T112 and T125, drops. After T112 has been opened, relay 19 is held in 75 the following circuit in which relay 19' is ener-

gized; battery, upper windings of 19 and 19', T191, T45 and earth.

The circuit of relay 12 is opened at T112, but said relay is short-circuited by T126 and R111 and is retarded. During the whole period of the energization of relay 12, a short A. C. impulse is transmitted via T121 and T124 and the relay 13 is energized. This relay, whose dropping has been retarded by its upper winding which is short-circuited at T131, causes the line to be released after the drop of 12 by short-circuiting at 132.

When the operator at the outgoing end operates her calling key, a new long A. C. impulse is received at the incoming exchange and energizes relay 2 for the holding impulse.

Relay 1, whose circuit is opened at R21, drops. The following circuit for relay 18 is closed: battery, winding of 18, R182', T44, R11 and earth. When the impulse has been received, relay 2 drops and relay 1 is re-energized. Relay 18 is maintained in series with relay 18' which is energized by T181 and T45. The driving circuit of the pre-selector Co7 is completed as follows: battery, magnet Cm7 of Co7 and its contact, T181', T183', R181, wiper T2 of Co7 and earth on the bank contacts of the junction line leading to the engaged incoming boards.

When the wipers of Co7 arrive on the bank contacts of a free line, the earth on wiper T2 is cut off. Relay 18' is energized on its lower winding via: earth, lower winding of 18, T181', contact and magnet Cm7 and battery. The preselector Co7 stops, its circuit being opened at R101.

A group of operator's calling relays, such as those of Fig. 4, is then connected to the equipment of Fig. 6. The busying of the line is caused by earth of T181 on the wiper T2.

The calling of the operator takes place as in the operation of the device in Fig. 4. When the incoming operator replies to a call, an earth is applied to wiper T1 by the equipment in Fig. 4. This earth energizes via T103 relay 6, which completes the following circuit for relay 11: battery, resistance R3, winding of 11, T191, T61, T42 and earth. The relay 12 is energized on the same circuit by T112. The following circuit of the lower winding of relay 19 is completed: battery, lower winding of 19, T192', T123, T112, T191', T61, T42 and earth. The two windings of the relay 19, being in opposition, said relay drops. The relay 19' is held in the same circuit through its lower winding.

While relay 12 is held, a short impulse is sent to the outgoing exchange. Relays 11 and 12 drop. Relay 19 drops, its circuit being opened at T123. The call is established via: conductor L1, R132' (Fig. 1) conductor A, R124 (Fig. 6) T105, wiper A, equipment of Fig. 4 and incoming board, wiper B, T102, R121, conductor B, R131' (Fig. 1) conductor L2.

When the call has been completed and the outgoing operator disconnects, a long A. C. impulse is transmitted by the outgoing exchange to energize relay 2. Relay 1, whose circuit is opened at R21, drops. Relay 5 drops, being short-circuited via: earth, R11, T44 and T182'.

When the impulse terminates, relay 2 drops. Relay 4 drops, being short-circuited via: earth, R21, R51 and T41. At T45, it closes the circuit of relays 18 and 18', which drop. At T181', relay 18' opens the circuit of relay 19, which drops. Relay 6 drops, its circuit having been opened at T103. The relay 3 is re-energized by R41, R51 and R21.

In the case where the incoming operator is the first to disconnect, the circuit of relay 6 is opened in wiper T1. In consequence of the operation of relays 11, 12, 19 and 19', via R61 and R191', a short supervisory impulse is sent to the outgoing exchange.

When the outgoing operator disconnects, the release takes place. Relays 19 and 19' drop after 4, their circuit being opened at T45.

10 The equipment in Fig. 6 may be released, when a call has not been completed, in the following manner:

When the equipment is seized, relay 20 is energized by cam 2 via the circuit: battery, lower winding of 20, R102, R34 and earth, through cam 1. It is held by its upper winding via T201, R104, and T45.

If the outgoing operator does not operate her calling key, then the second A. C. impulse is not received, and the relay 10 cannot be energized. 20 After a certain lapse of time, the relay 20' is energized by cam 2 on its lower winding via T203. It is held on its upper winding via T201, R104 and T45. Relay 5 is short-circuited at T202' and drops. Relay 1 drops, its circuit being opened at T51. Relay 4, short-circuited by T41, R51 and R1, drops. Relays 19, 19', 18, 18', 20 and 20' drop, their circuits being opened at T45.

The equipment is now free.

What is claimed is:

1. In a telephone system, a plurality of exchanges, toll trunk lines interconnecting the exchanges, subscribers' lines terminating at each exchange, switches at each exchange for connecting with called subscribers theret, toll operators' positions at said exchanges, outgoing and incoming equipment and sources of alternating current of a predetermined frequency at each exchange, means at a calling and a called exchange for connecting said equipments with a trunk, means in the outgoing equipment of the calling exchange and controlled by the outgoing operator for transmitting relatively long alternating current impulses from the calling exchange to operate and to release the incoming equipment at the called exchange, and means in the incoming equipment at the called exchange for transmitting relatively short alternating current impulses to control the outgoing equipment at the calling exchange.

2. The telephone system according to claim 1 and a relay in the outgoing equipment of the calling exchange controlled by the outgoing operator for disconnecting said equipment from the incoming equipment and connecting it with a toll trunk.

3. The telephone system according to claim 1, and in which the outgoing operator's position comprises a calling device operable in accordance with the digits of the called number, means operable upon the connection of the incoming equipment at the called exchange with a trunk for sending a relatively short A. C. impulse over the trunk to the outgoing equipment of the calling exchange, a relay in the last-mentioned equipment responsive to said impulse for signalling the outgoing operator, a second relay in the outgoing equipment controlled by the calling device for connecting the A. C. source with the trunk for relatively long periods of time in accordance with each digit of the called number, means in the input equipment of the called exchange responsive to long A. C. impulses for operating the switches at the exchange for selecting the called line.

4. The telephone system according to claim 1, 75 means in the outgoing equipment of the calling

25

exchange and controlled by the outgoing operator for sending relatively long A. C. impulses over a trunk, and means in the incoming equipment of the called exchange connected with said trunk and responsive to said impulses for signalling an operator at the called exchange.

5. The telephone system according to claim 1, means in the incoming equipment at the called exchange and controlled by the called subscriber for sending relatively short A. C. impulses over the connected trunk, and relay means in the outgoing equipment at the calling exchange responsive to said short impulses.

6. The telephone system according to claim 1, means in the incoming equipment at the called exchange controlled by an operator at the called exchange for sending relatively short A. C. impulses over the connected trunk, and relay means in the outgoing equipment at the calling exchange responsive to said short impulses.

7. The telephone system according to claim 1, means in the incoming equipment at the called exchange responsive to the connection of said incoming equipment with a trunk for sending relatively short A. C. impulses over the connected trunk, and relay means in the outgoing equipment at the calling exchange responsive to said short impulses.

8. In a telephone system, a plurality of exchanges, toll lines interconnecting the exchanges, 30 subscribers' lines terminating at each exchange, switches at each exchange for connecting with called subscribers thereat, toll operators' positions at said exchanges, calling devices at said positions operable in accordance with the digits of the 35

26

called number, outgoing and incoming equipment and sources of alternating current of a predetermined frequency at each exchange, means for connecting the outgoing equipment of the calling exchange with one end and the incoming equipment of the called exchange with the other end of a trunk, means in the outgoing equipment of the calling exchange and controlled by the outgoing operator for transmitting a relatively long alternating current impulse, means operative thereupon for connecting an impulse register with the connected incoming equipment, means controlled by the calling device of the outgoing operator for sending long A. C. impulses over the connected trunk to said register, means in the register responsive to said A. C. impulses for sending impulses to operate the switches at the called exchange for selecting the called subscriber, and means in the incoming equipment at the called exchange for transmitting relatively short alternating current impulses to control the outgoing equipment at the calling exchange.

CLAUDIUS F. STEWART.
